A. Bligham,
Attorney.

UNITED STATES PATENT OFFICE.

JAMES W. RUSSELL, OF SAN DIEGO, CALIFORNIA.

SHIP.

1,377,222.

Specification of Letters Patent. Patented May 10, 1921.

Application filed May 31, 1918. Serial No. 237,628.

To all whom it may concern:

Be it known that I, JAMES W. RUSSELL, a citizen of the United States, and a resident of San Diego, in the county of San Diego 5 and State of California, have invented certain new and useful Improvements in Ships, of which the following is a full, clear, and exact specification.

All kinds of ships have been sunk from 10 collisions, and in times of war have been sunk from shell fire and torpedoes; and sadly numerous as the latter have been, the continuous loss from collisions in times of peace as well as of war, with other craft or 15 with icebergs, as well as from striking rocks and reefs, is startlingly great.

The object of this invention is the construction of a safety ship, a ship substantially unsinkable, practical in design, adapted 20 for either passengers, freight or other uses, and which shall possess the following advantageous features: First, a large measure of protection against collision, shell fire, torpedoes and the like; which provides for 25 reserve buoyancy, diminishes the vessel's tendency to rolling and plunging, gives protected spaces for life boats and life rafts, and provides an improved system of bulkheads and pockets for the storage of shields 30 against torpedoes when not in use.

All these desirable purposes and others hereinafter set forth are accomplished by the construction illustrated in the drawings forming part of this specification, in which 35 drawings, Figure 1 is a cross section of a vessel, primarily designed for freight transportation, embodying my improvements. Fig. 2 is a plan view of the same in diagram, upon a smaller scale and with the central 40 portion of the vessel omitted.

The reference character 1 designates a ship having my improvements applied thereto. Upon each side of the ship, preferably extending from stem to stern and from the 45 water line to the level of the main deck, is formed a structure 2 reaching outward for several feet and diminishing in height as its distance from the side of the vessel increases. I prefer to have both its top 3 and 50 bottom 4 inclined, and to have the outer wall 5 only a few feet or inches in height.

This structure 2, which covers or replaces wholly or in part, the vertical freeboard 6 of the ship, I prefer to call a chambered 55 buffer, and to have the same both watertight and practically air-tight. Midway be-

tween the top 3 and bottom 4 of each chambered buffer is an intermediate floor 7, preferably on the same level with or an extension of the deck 9 of the ship. Upon this floor 60 may be located the vessel's life boats 10 and life rafts 11, the top 3 being formed with suitable hatchways 12 adapted to be normally closed water-tight, but to be easily and quickly opened for the removal of the 65 boats and rafts.

For handling the life boats and life rafts, and for lowering them to the water beyond the buffers 2 and the shields 13 which I design to locate several feet farther out from 70 the buffers, I provide the ship with a number of booms 14, the ropes 15 of which can be attached to the boats and rafts for hoisting them singly from their resting places and depositing them safely in the water. 75 For this purpose, each boom should be longer than the distance from the foot of its mast 17 to a point three or four feet outside the shields 13.

Should, now, a steamship crash against 80 the ship 1, the chambered buffer 2 will give sufficient resistance to the steamship to prevent its cutting into the body of the ship itself, even if the oncoming vessel strikes it bow on. Similarly, an iceberg is warded 85 from dangerously injuring the ship provided with my chambered buffer.

In case a hidden reef or projecting rock should cut a dangerous hole in the ship's bottom or side, the inrushing water will simply sink the ship to a point where the buoyancy of the chambered buffers 2 can act to sustain it. 90

When the vessel 1 rolls or plunges, the chambered buffers meet the water and by 95 their buoyant effect greatly reduce such motion. Were the under surface or bottom 4 of the chambered buffers made to be horizontal, the blow of the same upon the surface of the water as the vessel rolls would be 100 quite severe, but by having it inclined upward from a point near the water line of the vessel, this lowermost section of the surface 4 descends into the water first and then point after point until much of the surface 105 is submerged, all without shock or disturbance, except under unusual conditions of wind and wave.

For protection against torpedoes and the like, a series of floating shields 13 are provided, which are made sufficiently buoyant and loaded at their lower edges to float ver-

tically with their upper edges nearly on the same level as the outer extremity of the bottom 4, or otherwise somewhat above the water line. Each shield 13 is connected by two 5 or more arms 19, pivoted at their ends to the shield and to the outer extremity of the buffer so that it can rise and fall to a limited extent independently of the vessel. The length of these arms added to the reach of 10 the chambered buffers gives a distance of the shields from the sides of the ship which will insure against material injury to the latter arising from the explosion of a torpedo or of a drifting mine against one of the 15 shields.

These pivoted arms serve not only to hold the shields at the required distance from the ship, and permit free vertical movement thereof, but give them play independently of each other to meet the requirements of wave motion, the effect of which upon the ship and shield will not always be concurrent, nor of one shield to its neighbors. 20

The shields are preferably disposed end 25 to end for substantially the entire length of the ship, being stepped at the bow and stern to remain at the desired distance therefrom while held parallel with the line of progress of the ship in order to cut freely 30 through the water.

The shields may be used only when the ship is passing through a danger zone, and to that end they are detachable so that they can be taken up by a boom 14 and swung 35 over into suitable pockets 20 provided for them in the ship. These pockets are preferably formed beside the vertical bulkheads 21 by which the ship is divided into three sets of longitudinally extending water-tight 40 compartments; the sets of compartments 22 being between the ship's sides and the bulkheads 21, and the set 23 being between the bulkheads 21.

Hence, should a torpedo or a floating mine 45 explode in contact with the sides of the ship because the shields 13 had been removed from the water and deposited in the pockets 20, the shields would protect the bulkheads from the explosion and limit the 50 destructive effect of the same.

Further, by having the compartments 22 comparatively small, any water entering a torpedoed side of the ship is restricted in 55 volume to such small compartments and is consequently insufficient to sink the ship, or to reach and damage much of the cargo. In addition, by having the pockets 20 reach to as low a point as practicable in the ship, the weight of the shields 13 when stored 60 therein, will be located correspondingly low, and the stability of the ship will be increased.

For the sake of economy and speed in construction, the chambered buffer 2 is preferably made without curves, so that the 65

plates and girders need not be bent, but otherwise there is no objection and perhaps some advantages in curving the parts.

To recapitulate, the stability of a ship will be greatly increased by the chambered buffers, a most important feature. Among heavy waves and exposed to strong wind pressure, the improved ship will suffer far less than those hitherto built. As this ship heels, or starts to roll, the projecting buffer 70 2 on the lee side meets the water and forms a supporting and steadyng surface which will greatly reduce both the roll and the plunge of the ship, so that I am led to believe that it will be found next to impossible 75 for my improved ship to founder or capsize. 80

Further, should a shell, torpedo or mine penetrate the vessel below the water line, the reserve buoyancy of the chambered buffers 2 will amply compensate for that lost by the 85 flooding of one or more compartments of the ship and such reserve buoyancy becomes operatively effective automatically with the settling of the ship.

In case of a collision with another vessel, 90 or with an iceberg, the buffer 2 will offer sufficient resistance to insure against dangerous injury to the main sides of the ship; but in case water did enter a compartment, the ship remains safe, for the reason of the 95 reserve buoyancy of the chambered buffers as already recited.

The flat vertical sides of ships as now built 100 form excellent targets for enemy guns; the direct impact of a shell against the flat surface being far more effective than the glancing hit against the sloping top 3 of the buffers 2. Even should a shell pierce a buffer 2, it in all probability would not also 105 pierce a vital part of the ship.

In order to protect a ship from a torpedo, it is best to intercept and explode the latter at a substantial distance from the ship. To accomplish this by long arms reaching out 110 from the sides of the vessel is not found to be satisfactory, but by the employment of comparatively short arms carried outward to the total distance necessary for safety by means of the chambered buffers, the objections are overcome, and the shields are suitably spaced from the ship's hull in a manner 115 to be eminently practical even in foul weather.

Shell fire that falls short and might otherwise strike the ship below the water line, 120 will in the great majority of cases meet one of the shields 13 and be either intercepted or its destructive force greatly reduced.

These chambered buffers may be readily attached to some ships now in use or under 125 construction, as well as those planned therefor in the beginning.

Some vessels have been provided with water-tight bulkheads inadequate in number if not faulty in design or arrangement. I 130

have endeavored to overcome such defects by dividing my ship into several water-tight compartments located next to the wall of the ship, as at 21, extending from the bottom 5 of the ship up to its deck 8 well above the water line. This deck 8 should also be water-tight, as also that section 25 of each deck between these main longitudinal bulkheads 21 and the outer shell or skin of the ship. 10 The deck 26 located nearest the bottom of the hull, should be water-tight in its entirety; and between this deck and the bottom of the hull is located a bulkhead 27 on the center longitudinal line of the ship.

15 By this system of water-tight compartments, when the outer shell or skin of the ship is pierced, the incoming water is restricted to the outer areas of the ship, thus saving a large space in the center of the ship 20 that will be comparatively safe and free from water, even should other of the compartments become flooded.

Naturally, this system of compartments may have to be modified somewhat in the section 25 of the vessel occupied by the boilers and engines.

Cross bulkheads 28 should, of course, be used, depending in number upon the length 30 of the ship, as indicated in Fig. 2. Likewise, each hollow buffer 2 is divided by transverse bulkheads 30 into sufficient compartments to insure against more than a short section thereof being flooded in case of a collision.

What I claim is:

35 1. A ship having three decks, in combination with a water-tight buffer for each side thereof located entirely above the normal water-line of the ship, the under side of each buffer being substantially flat and inclined 40 upward toward its outer limits, the upper surface of each buffer being substantially flat

and inclined downward toward its outer limits, each buffer having a horizontal floor intermediate of its top and bottom in line with a deck of the ship, and the top and bottom 45 of each buffer being attached to the ship at the levels of other decks.

2. A ship in combination with a water-tight buffer for each side thereof located above the normal water-line thereof, each 50 buffer comprising a top and bottom each oblique to the horizon and approaching each other at their outer limits, and a low substantially vertical wall uniting the outer limits of the top and bottom of each buffer. 55

3. A ship in combination with a buffer for each side thereof projecting for a considerable distance from the ship's sides, arms pivoted to the outer extremities of each buffer and reaching out therefrom, and buoyant 60 shields pivotally attached to the outer ends of said arms.

4. A ship having shields detachably connected with its sides, and vertical pockets reaching substantially to the bottom of the 65 ship for receiving said shields when not in use, whereby the ship can keep its center of gravity at the lowest desirable point relative to its center of buoyancy.

5. A ship having shields detachably connected with its exterior, vertical longitudinal bulkheads spaced from the sides of the ship, and pockets for said shields located on the side of each bulkhead next to the adjacent side of the ship, whereby the stored shields 75 protect the bulkheads from penetration and injury by torpedoes.

In testimony that I claim the foregoing invention, I have hereunto set my hand this 27th day of May, 1918.

JAMES W. RUSSELL.
